FIG. 1.

FIG. 2.

Gustave M. Minton Inventor
By his Attorney Charles G. Neusley

UNITED STATES PATENT OFFICE.

GUSTAVE M. MINTON, OF NEW YORK, N. Y.

DESIGN FOR A MATCH AND CIGARETTE HOLDER FOR SMOKERS' SETS.

60,199.

Specification for Design.

Patented Jan. 10, 1922.

Application filed April 21, 1921. Serial No. 463,394. Term of patent 3½ years.

To all whom it may concern:

Be it known that I, GUSTAVE M. MINTON, a citizen of the United States, residing in the city, county, and State of New York, have invented a new, original, and ornamental Design for a Match and Cigarette Holder for Smokers' Sets, of which the following is a specification, reference being had to the accompanying drawing, forming part hereof.

Figure 1 is a side elevation and Figure 2 is an end elevation of a match and cigarette holder for a smoker's set, showing my new design.

I claim:

The ornamental design for a match and cigarette holder for smokers' sets, as shown.

GUSTAVE M. MINTON.
